MECHANICO-FLUID-PRESSURE METHOD OF
PRODUCING LATERAL-PROVIDED FIT-
TINGS

Edward S. Cornell, Jr., Larchmont, N. Y.

Application December 6, 1937, Serial No. 178,278

3 Claims. (Cl. 29—157)

My invention relates to a combined mechanical and fluid pressure method of producing lateral-provided fittings.

The method is particularly applicable to the production of T's provided with one or more laterals, the T resulting from my process having its lateral integral of itself, its body inclusive of the walls of its end openings integral individually and the stated parts integral with one another, thereby producing a T or other lateral-provided fitting wholly without joint.

My invention is of particular advantage in the production of T's and other lateral-provided fittings from commercially pure copper and alloys of predominant copper content, and in the absence of supplied elevated temperature capable, in the use of copper or alloys of predominant copper content, of forming cuprous oxids or otherwise giving rise to deleterious working conditions.

20 In general, my method comprises the employment of a length of tube of the desired metal constituency, subjecting such tube in a suitable device, as in a die having main and lateral apertures corresponding to the contour of the desired 25 T or other lateral-provided fitting, and subjecting such tube to combined mechanical pressure with respect to the walls of the tube and fluid pressure internally of the tube, to derive the desired T or other lateral-provided fitting.

30 Advantageously, such combined mechanical and internal fluid pressures are effected by suitable punches or male die members, suitably shaped and dimensioned to simultaneously effect, as when actuated by a press or the like, bodily 35 pressure endwise of the tube, in approaching directions toward the central portion of the tube, and the building up and maintenance of pressure of the fluid medium internally of the tube, whereby the metal of the tube is caused to flow in 40 approaching directions from the respective ends of the tube toward the central portion of the tube and into the one or more lateral apertures of the die.

A particular feature of the present invention 45 resides in the employment of one or more punches having a relatively elongated nose, the periphery of which conforms closely to the internal diameter of the tube, such nose extending to or beyond the region of the juncture of the "run" aperture 50 of the die with the one or more lateral apertures of the die, the "run" being understood as the interior of the body of the T or other lateral-provided fitting, as distinguished from the interior of the one or more laterals. By the employment 55 of such one or more relatively long nosed

punches, upon the application of bodily pressure endwise of the tube, the cylindrical or other original formation of the tube is maintained. Advantageously, the formation of the terminal portion of such one or more relatively long nosed 5 punches facilitates the flow of the oil or other fluid medium effecting the internal fluid pressure, in the direction of the lateral or directions of the respective laterals.

The above stated process gives rise directly to a 10 body of a T or the like having a lateral formation. Subsequent and/or finishing operations may then be carried out, to derive particular characteristics of body and/or lateral configurations, as may be desired.

15 Further features and objects of the invention will be more fully understood from the following detail description and the accompanying drawing, in which

Fig. 1 is a longitudinal central section of a T, 20 capable of being produced by the method of my present invention;

Fig. 2 is a side elevation, partly broken away in central section, illustrating a length of tube, serving as the original "work", for producing a T 25 of the type illustrated in Fig. 1;

Fig. 3 is an exploded view, diagrammatically shown in side elevation, of a two-part split die, suitable for the reception of the length of tube, shown in Fig. 2, and a pair of relatively long 30 nosed punches or male dies, appropriate for application of bodily endwise mechanical pressure upon the thus positioned length of tube;

Fig. 4 illustrates diagrammatically, corresponding to Fig. 3, the positioning of the length 35 of tube and the respective relatively long nosed punches, together with a predetermined quantity of oil or other fluid medium internally of the tube and between the noses of the respective punches, preparatory for the application of pressure upon the punches, to effect bodily pressure upon the material of the tube, endwise in directions toward the central portion of the tube and therewith concurrent building up and maintenance of the fluid pressure internally of the tube; 45

Fig. 5 is a diagrammatic view, corresponding to that of Fig. 4, illustrating a final stage of combined body pressure, endwise of the material of the tube toward its central portion and concurrent building up and maintenance of fluid pressure internally of the tube, whereby there is formed by my method, a lateral having outer dimensions and configurations, predetermined by the lateral aperture of the die;

(It is observed from Figs. 4 and 5, that a plug 55

having a convex effective face, may be employed in, and serving as a closure for the lateral opening of the die, giving rise to a concave "dome" formation at the terminus of the lateral.)

5 Fig. 6 is a central longitudinal section of the lateral-provided formation, of the tube shown in Fig. 2, resulting from the operations indicated in Figs. 4 and 5, the "dome" of the lateral being indicated as separated, i. e. severed, at the terminus of the lateral;

10 Fig. 7 is a detail view indicating one manner of expanding an end opening of the T formation shown in Fig. 6, to derive an end opening—and likewise a lateral opening—of the type indicated 15 in Fig. 1.

As indicated herein, my present method is applicable for the production of T's and other lateral-provided fittings, with such inner and outer diameters, wall thicknesses, relative lengths of 20 body end openings and lateral or laterals, ad libitum, as may be desired. Accordingly, the T 10 illustrated in Fig. 1 serves merely to indicate a type of T which is producible pursuant to my method. With respect to the T 10, illustrated in 25 Fig. 1, 10a indicates one end opening, 10b the opposite end opening, 10c the lateral opening, and 10d the body. Desirably, as is indicated in Fig. 1, each end opening and the lateral opening is provided with an abutment, indicated at 10e, 30 applicable to serve as a stop for the reception of the end of a pipe, telescopically inserted within such opening or openings, for connection therein, as by sweat jointing.

Applicable for the production of a T, such as 35 the type indicated in Fig. 1, I employ a length of tube 11, see Fig. 2, as the "work," which is subjected to combined bodily endwise pressure and internal fluid pressure. Such tube 11 is preferably of commercially pure copper or of alloy of 40 predominant copper content. Advantageously, the wall thickness, see 11a, is selected in correspondence to the wall thickness, see 10f, Fig. 1, of the body of the resulting T. By reason of the 45 characteristic operation features of my invention, the cubical content of the tube 11, is predetermined for minimum waste, as appears more fully hereinafter.

Referring now to Figs. 3 and 4, such length of 50 tube 11 is positioned within a suitable instrumentation, such as the indicated two-part split die, indicated generally by the reference number 12, such die being provided with an aperture 12a extending in the direction of the "run" of the die and the desired one or more lateral apertures 12b.

In the specific die 12, illustrated in Figs. 3 and 4, the "run" or main aperture 12a and the single lateral aperture 12b correspond generally to the T formation shown in Fig. 1.

60 Upon suitably positioning such length of tube 11, serving as the "work," within such die 12, and closing the same, suitably nosed punches or male die members 13, 14, and a suitable fluid medium interposed within the tube and between 65 the noses of the punches, described more fully hereinafter, are employed to effect combined bodily endwise pressure and concurrently therewith internal fluid pressure, the actuation of such punches or male die members 13, 14, being had 70 by means of a suitable power press, or equivalent.

Desirably, the terminus 12b' of the lateral aperture 12b is provided with a plug 15, serving dually to control the terminal formation of 75 the resulting lateral and to "close" the lateral

aperture terminus 12b'. Advantageously, the effective face, see 15a, of such plug is of convex formation, attaining advantages as appear more fully hereinafter.

For the attainment of such combined bodily pressure and internal fluid pressure, such punches 13, 14, are respectively provided with abutments, see 13a, 14a, Figs. 3 and 4, advantageously formed by reduction of diameter, the reduced diameter of the resulting body 13b of the punch 10 13—likewise the reduced diameter of the body 14b of the nose of the punch 14—making a close, i. e., fluid medium proof, fit with the inner diameter of the "work" 11.

An important characteristic of my present invention resides in effecting in a positive manner the maintainance, i. e., preservation and without internal collapse and/or external deformation, of the original wall configuration of the "work" during the stage of flow of the material of the "work" in the directions from the regions of the ends of the "work" toward its central portion, including the preservation of the material of the wall portion of the "work" disposed adjacent to and within the region of juncture of the "run" 25 of the fitting with its lateral, and particularly that portion of the material of the "work" within the region of the stated juncture remote from the opening of the lateral, indicated by the reference character 11', see Fig. 4.

The attainment of such objectives is had by the employment, pursuant to one form of my method, of a relatively long nose for at least one of the punches, to bring about when such punch or punches are properly related to the "work," 30 when the same are assembled in the die, viz., at the stage indicated in Fig. 4, that such elongated nose or noses extend internally of the "work" to and within the zone of the die aperture common to the run and lateral portions thereof, i. e., the 40 region of juncture of the "run" of the fitting with the lateral of the fitting. As indicated in Figs. 3 and 4, the punch 13, is provided with a long nose, which extends to and within the stated region, and its terminal portion 13b' positively engaging the inner face of the "work" to positively preclude the collapse internally of the material—see 11', Fig. 4—the wall of the "run" aperture of the die precluding any tendency of external deformation of the "work." The terminal portion 14b' of the nose of the punch 14, as observed from Fig. 4, may extend approximately to the juncture of the "run" aperture 12a with the lateral aperture 12b.

Oil or other suitable medium normally flowable or capable of being rendered flowable under the pressure operation conditions, indicated 16, is disposed internally of the "work" 11 and interposed between the terminal portions of the noses of the respective punches 13, 14.

Upon application of force, as by a power press, upon the punches 13, 14, bodily pressure upon the material of the "work" is applied endwise of the "work" in directions toward the central portion of the "work" and concurrently therewith the building-up and maintenance of internal fluid pressure.

Fig. 5 indicates the resulting lateral formation of the "work," effected by the stated combined bodily and internal fluid pressures. By such combined bodily, endwise applied, pressure, and the stated concurrent internal fluid pressure, the material of the "work" is caused to flow in directions from the respective ends of the "work" toward its central portion and into and from the 75

region of the "run" aperture 12a of the die into and within the lateral aperture 12b of the die. In such operation, the abutment formations 13a, 14a, serve to respectively progress the end portions of the "work" longitudinally of the "run" aperture 12a of the die, while the outer peripheries of the respective elongated noses 13b and 14b of the punches 13, 14, maintain the cylindrical or other inner configuration of the "work," 5 the terminal portion 13b' of the punch 13, and to a degree of the terminal portion 14b' of the punch 14, by reason of their extension to and within the region of juncture of the "run" aperture 12a and lateral aperture 12b of the die, precluding "buckling" or other deformation of the "work" during such operation.

Preferably, as is illustrated in Figs. 3, 4 and 5, the terminal portions 13b' and 14b' are stepped in staggered relation, thus giving rise, as is indicated by comparison of the showings in Figs. 4 and 5, of a "channel" between the stated stepped terminal nose formations 13b' and 14b', serving to direct the fluid medium 16 toward and into the lateral aperture 12b, thus expediting the flow 20 of the metal into the lateral aperture 12b and toward and in pressure contact with the walls of the lateral aperture 12b of the die.

As appears, my invention enables the selection of the wall thickness of the "work" in correspondence to the desired wall thickness of the body of the resultant fitting, by reason of the preservation—and without collapse—of the original wall thickness of the "work," in carrying out my method.

35 In the stated, or equivalent, combined mechanical and internal fluid pressure operations, the contour of the lateral aperture 12b, predetermines the outer configuration of the resulting lateral formation. Desirably, as set forth more fully hereinabove, the employment of a plug 15, having a convex effective face formation 15a, or other desired effective face formation, controls the flow of the metal within the lateral aperture 12b of the die. The production of a dome, see 40 Figs. 5 and 6, of outer concave contour, resulting from the stated convex face formation 15a of the plug 15, reduces waste of material of the "work" to a minimum. As is indicated in Fig. 6, the terminal dome formation 11b is removed, as by severing the same from the lateral formation, thus giving rise to open ended lateral 45 11c, see Fig. 6. The body of the resulting lateral-provided, i. e., general T formation, illustrated in Fig. 6, is designated 11d and the respective body 50 end openings designated 11e and 11f.

Such resulting lateral-provided formation, indicated in Fig. 6, is then treated to such subsequent and/or finishing operations as may be desired, as by expanding the respective body end 55 openings 11e, 11f, as is indicated in Fig. 7, to derive a type of expanded body end openings 10a, 10b, illustrated in Fig. 1. A suitable form of expanding tool 17 and holding die 18 are indicated in Fig. 7.

60 In lieu of severing the dome formation at the terminal of the lateral formation, the material of the dome formation may be utilized, in subsequent operations, as by the well known ball procedure, to form an extension to the lateral formation effected by the stated concurrent bodily pressure and internal fluid pressure.

Commercially pure copper, or alloy of predominant copper content, is particularly applicable as the material of the "work" employable in carrying out my invention, affording cold

working of the "work," pursuant to the steps hereinabove set forth, thereby precluding the formation of cuprous oxides or other deleterious conditions.

5 In like manner, other types of lateral-provided fittings are produced by my method.

In the appended claims I define the term "lateral aperture" of the die as including not only one lateral aperture but such plurality of lateral apertures in the die as may be necessary to form the desired number of laterals at their respective desired locations of the resultant fitting.

10 In the appended claims I define the term "lateral" of the resultant fitting as including not only one lateral but such plurality of laterals as 15 may be desired in the resultant fitting.

Whereas I have described my invention by reference to specific forms thereof, it will be understood that many changes and modifications may 20 be made without departing from the spirit of the 25 invention.

I claim:

1. The method of producing a lateral-provided fitting of a desired metal having a desired wall thickness of its body, which comprises selecting a hollow length of the desired metal having a wall thickness corresponding to the stated body wall thickness of the fitting, such hollow length serving as the work, placing the work in a suitable die provided with a run aperture and a lateral aperture, inserting rigid members having a diameter substantially equal to the interior diameter of the work within said work, confining a body of liquid within said work intermediate 30 said rigid members, and applying endwise pressure to said work in direction from the respective ends thereof toward its central portion and concurrently therewith to fluid pressure internally of the work while initially supporting the wall of said work within the region within the juncture remote from the opening of said lateral by contact with said rigid element and a wall of said die and progressively increasing the area of said support as the material of the work under the stated concurrent bodily pressure and the internal fluid pressure is caused to flow from the wall 35 formation of the work into the lateral aperture 40 of the die.

2. The method of producing a lateral-provided fitting of a desired metal having a desired wall thickness of its body, which comprises selecting a hollow length of the desired metal having a wall thickness corresponding to the stated body wall thickness of the fitting, such hollow length serving as the work, placing the work in a suitable die provided with a run aperture and a lateral aperture, inserting rigid members having a diameter substantially equal to the interior diameter of the work within said work, confining a body of liquid within said work intermediate 50 said rigid members, and applying endwise pressure to said work in direction from the respective ends thereof toward its central portion and concurrently therewith to fluid pressure internally of the work while initially supporting the wall of said work within the region within the juncture remote from the opening of said lateral by contact with said rigid element and a wall of said die and progressively increasing the area of said support as the material of the work under the stated concurrent bodily pressure and the internal fluid pressure is caused to flow from the wall 55 formation of the work into the lateral aperture 60 of the die.

3. The method of producing a lateral-provided fitting of a desired metal having a desired wall thickness of its body, which comprises selecting a hollow length of the desired metal having a wall thickness corresponding to the stated body wall thickness of the fitting, such hollow length serving as the work, placing the work in a suitable die provided with a run aperture and a lateral aperture, inserting rigid members having a diameter substantially equal to the interior diameter of the work within said work, confining a body of liquid within said work intermediate 65 said rigid members, and applying endwise pressure to said work in direction from the respective ends thereof toward its central portion and concurrently therewith to fluid pressure internally of the work while initially supporting the wall of said work within the region within the juncture remote from the opening of said lateral by contact with said rigid element and a wall of said die and progressively increasing the area of said support while maintaining a channel for flow of the confined fluid from the "run" portion 70 of the said work into the lateral thereof as the material of the work under the stated concurrent bodily pressure and the internal fluid pres- 75

sure is caused to flow from the wall formation of the work into the lateral aperture of the die.

3. The method of producing a lateral-provided fitting, which includes the steps of positioning 5 a tubular length of metal serving as the "work" within a die having a "run" aperture adapted to form the run of the fitting and a "lateral" aperture for forming the lateral of such fitting, inserting punch means having an outside diameter 10 substantially equal to the internal diameter of the work into the work to support the wall of the work in contact with the walls of the die at locations adjacent the intersection of the wall of the lateral aperture with the wall of the run aperture and to support the wall of said work 15 in the zone of the apertures of the die common to the run and lateral thereof, confining a body of liquid within the work and applying pressure

to the end walls of the work in direction from the respective ends thereof and concurrently therewith applying fluid pressure internally of the work, to flow the material of the work laterally of itself and angularly of its longitudinal axis into the lateral aperture of the die to form a lateral branch of the fitting while moving said punch means to continually support the walls of the work between said punch means and the walls of the die at the area of intersection of the 10 wall of the lateral aperture with the wall of the run aperture and progressively to increase the area of engagement of said punch means with the wall of the work in the aforementioned zone to an ultimate condition wherein substantially 15 all of the wall of the work in such zone is engaged by said punch means.

EDWARD S. CORNELL, JR.
